UNITED STATES PATENT OFFICE.

DENIS J. O'SULLIVAN, OF ROME, NEW YORK.

COMBINATION LOCK.

Application filed October 24, 1921. Serial No. 510,043.

To all whom it may concern:

Be it known that I, DENIS J. O'SULLIVAN, a citizen of the United States, and a resident of Rome, county of Oneida, State of New York, have invented certain new and useful Improvements in Combination Locks, of which the following is a specification.

This invention relates to combination locks, principally for locking railway car doors. The door is locked by an ordinary hook latch, the same being hooked firmly inside a chamber which is provided with a door, and which in turn is locked by the combination lock.

15 The object of this invention is to provide a new and novel means of the combination type for locking the door of a chamber in which the primary locking of the principle element is accomplished.

20 A further object is to provide a lock of the combination type, whereby the key parts for manipulating the combination may be removed, and any one desiring to open the lock must have a key or keys in addition to knowing the index numbers for opening the same.

In conjunction with the above stated objects a further object is to provide a lock which can be pre-arranged by the man who does the locking, in that the mode or procedure of following out the index numbers of the combination for manipulating the lock may be changed; and also a lock in which the mechanism as a whole can readily be taken out of the chamber and a new one substituted therefor, in the event that the same becomes disarranged or gets out of order.

This invention will be more fully understood and other objects will be apparent, from the following description taken in connection with the accompanying drawings, forming a part hereof, and in which similar numerals refer to similar parts throughout the several views.

Fig. 1, represents the lock arranged in combination with a freight car door.

Figs. 2 and 3 are keys for manipulating the lock.

50 Fig. 4, shows the lock as it appears when the chamber doors are closed.

Fig. 5, is a view from the inside of the

chamber showing the latch for holding the door 1 of Fig. 4, closed.

Fig. 6, is a sectional view taken on line 55 6—6 of Fig. 10 and shows the door 2 of Fig. 4 partly open.

Fig. 7, shows the inside of the chamber; the doors 1 and 2 being removed.

Fig. 8, is a perspective view of a portion 60 of the lock.

Fig. 9, is a sectional view taken on line 9—9 of Fig. 4.

Fig. 10, shows the inside of the chamber, the doors 1 and 2 being removed, and the 65 locking mechanism in a different position from that shown in Fig. 7.

Referring to the drawings, 3 is a portion of the side wall of a freight car. 4 is a portion of the car door; the same being mounted on rollers and free to slide in the usual manner. 5 is a door latch, pivoted to the door 4 as shown at 7, Fig. 1. The locking mechanism 8, Fig. 1—also shown enlarged in Figs. 7 and 10—is fitted in the chamber 75 9 as shown. The door 1 is carried by the hinges 10 and the door 2 by the hinges 11. The door 1 is held closed by the latch shown in Fig. 5, in which 12 is a U shaped block substantially forming a part of the wall 14, 80 and 15 is a block substantially forming a part of the door 1 and carries the swivel hook 16. It is obvious that by giving the swivel hook 16 one-quarter turn, the door 1 can be opened. Access to the latch shown in 85 Fig. 5 can be had only when the door 2 is open.

Fitted in the bottom of the chamber 9 is a base plate 17, the same being free to slide and guided by the tongue and groove shown 90 at 18. Carried by the base plate 17 is a plate 20 which is free to slide and is guided by projections 21 and 22 of the base plate 17. The plate 20 is provided with four slots 23 into which engages lock strips 24 when the 95 locking element 19 is down as shown in Figs. 9 and 10. The sliding plate 20 is further provided with a notch 25 into which engages the latch 26, the same being carried by the door 2 as shown in Fig. 6. The latch 100 26 is pivoted on the pin 27, and adaptable to engage with the sliding plate 20, and lock the door 2 closed as shown in Fig. 9.

Carried by the base plate 17 are four

standards 28 which carry the top plate 29. Forming a part of the standards 28 are projecting lugs 30 which project through openings in the plates 29 as shown. Through 5 holes in the projecting lugs 30 are fitted pins 31 which must be removed when it is desired to remove the plates 29. Between the standards 28 are a series of partitions 32 which form compartments 33. Into these compartments 10 are fitted locking levers 34. The locking levers 34 are pivoted on the pins 37, and the ends thereof project above the plates 29 through openings 35 as shown.

Pivoted on the lower ends of the locking 15 levers 34 are locking blocks 36, which are so arranged that when the locking levers 34 are turned to the proper position on the pivot pins 37, the locking blocks 36 may be positioned through the slots 38, and into the 20 channels 43, thereby preventing the hinged element 19 from being opened to the position shown in Fig. 7.

By examining Fig. 9, wherein the locking blocks 36 are positioned to engage through 25 the slots 38 and into the channels 43, it is obvious that the locking blocks 36 might be changed to the position indicated by dotted lines at 36' they would then be positioned to engage through the slots 38' into 30 the opening 42, and in this manner lock the hinged element 19 from being opened. The object of this, is that the man who locks the car door may arrange the locking blocks 36 to suit his own choice, some 35 to the right and some to the left, and no one except himself knows which direction the locking levers 34 must be moved to release the hinged element 19 from the locked condition. He of course makes a record of how he has arranged these locking elements and forwards the same to the man who is permitted to open the lock.

The side plates 39 are pivoted to the base plate 17 at the point 40, so that they can 45 be swung outward to observe the condition of the locking blocks 36. The center beam 41 forms a part of the base plate 17 and is provided with an opening 42 into which fit the locking blocks 36. The side strips 39 50 are each provided with a hole 44 which engages the pins 45; these pins being carried by hinged element 19, holds the side plates 39 in vertical position when the hinged element 19 is down.

Carried by the hinged element 19 are 55 standards 46 which carry the rods 47; they form guides upon which is mounted cross head 48 in a manner free to slide in either direction, indicated by arrow 50. Carried 60 by the cross head 48 is a sliding block 51 mounted in a manner free to slide in either direction indicated by arrow 52. Forming a part of the sliding block 51 are projecting lugs 54 which are adapted to engage with 65 the end 55 of any of the locking levers 34.

Through the manipulation of the sliding block 51, the locking blocks 36 may be positioned through the locking levers 34 and the lugs 54 to lock the hinged element 19 down through the locking levers 34 and the 70 lugs 54.

The cross head 48 is provided with an opening 56 adapted to receive a key 57. Fig. 2, represents a perspective view of the key 57, the same being constructed of a flat 75 strip 58 which is provided with a lug 59 and an opening 60; the strip 61 is provided with an opening 62 which engages the lug 59. The opening 60 engages with the lug 63 of sliding block 51, as shown in Fig. 9, 80 and thereby the sliding block 51 can be manipulated for positioning the locking block 36.

The door 2 is provided with an opening 64 through which the key 57 may be inserted in the cross head 48. A sliding block 65 is carried by the guide strip 66 forming a part of the door 2; it is also provided with an opening 67 through which the key 57 is placed, and is carried with any movement of the key 57 in the direction indicated by the arrow 68. The block 65 is further provided with a pointer 69, and the guide strip 66 is stamped with index numbers 1 to 10 as shown. The object of the 95 index numbers, is to guide the operator in locating the cross head 48 so that the lugs 54 will engage with the ends 55 of the levers 34.

The method of manipulating this lock is 100 as follows:—First assume that the operator desires to lock the car and prearrange the combination for opening the same to suit his own choice; the car door is locked in the ordinary manner by the hook latch 5, the 105 same engaging with the block 70 which prevents the car door from being opened from the outside. The locking mechanism is removed from the compartment 9 and the hinged element 19 is removed from the base plate 17, by taking out the pin 71; then he removes the pins 31; takes off the plates 29 and pulls out the pivot pins 37. He then arranges the locking blocks 36 relative to the locking levers 34 115 to suit his own choice, and re-assembles the device as shown in Fig. 8. The hinged element 19 is then replaced and the complete locking mechanism is again placed in the compartment 9. The door 1 is then closed 120 and latched by the latch shown in Fig. 5; the door 2 is closed and the latch 26 is caused to engage with the sliding plate 20 as shown in Fig. 9. The hinged element 19, is then lowered to its full extent as 125 shown in Fig. 10, the same being accomplished by inserting the flat portion 74 of the key shown in Fig. 3 through the aperture 72 in the door 2, and into the opening 75 of the hinged element 19. When the 130

hinged element 19 is lowered to its full extent, the key 57 is inserted through the sliding block 65 and into the cross head 48; the parts 58 and 61 being arranged and associated in conjunction with the cross head 48 and the lugs 63 as shown in Fig. 9. The procedure of locking the hinged element 19 in its down position, is by manipulating the key 57, moving the same in the direction indicated by the arrow 68, stopping the pointer 69 at each of the indexed members 1 to 10, and moving the key 57 in or out as indicated by the arrow 52, and as required for positioning the locking blocks 36 for locking the hinged element 19 down. The keys 57 and 74 are then removed and the lock operation is complete.

The operation for unlocking the lock is accomplished in substantially the same manner, except that the locking levers 34 are moved in the proper position for disengaging the locking blocks 36 through the slots 38 and 38'.

The man who receives the car is provided with duplicate keys like that shown in Figs. 2 and 3, and is also provided with a record of the locking combination by the man who did the locking; this will enable him to open the lock.

I herein show and describe locking levers 34, but it is obvious that this number may be more or less, the difference being, only in that a greater or less number of different combinations can be had.

To prevent the hook 5 from becoming disengaged with the locking blocks 70 through vibration from the bumping of the train; I provide a block 76, which is pivoted at 77 to the bracket 78, the same being carried by the side wall 14 of the chamber 9. By examining Figs. 7 and 10 it will be obvious that the hook 5 cannot be disengaged from the locking blocks 70 unless the block 76 is given a quarter turn on the pivot pin 77.

This whole mechanism is so arranged that access to the hook 5 and the block 76 cannot be had except when the door 1, or 2 is opened. I have herein shown and described this lock as being applicable for locking railway car doors, but it is obvious however that the same may be used for locking anything of the character whereby it can be accomplished by inclosing a hook or locking element in a chamber; or the chamber 9 might be made large and be employed as the safe deposit chamber for securing valuable articles.

Having thus described my invention, what I claim as new and desire to secure by United States Letters Patent is as follows:

1. The combination of a latch chamber, a removable locking device in said chamber, a door which partially closes said chamber and prevents said locking device from being removed, a second door which completes the closing of said chamber, means for locking

the first said door closed, access thereto being possible only through the opening provided by second said door, and means for locking the second said door closed through the first said locking device. 70

2. The combination of a latch chamber, a slideable plate in said chamber, a locking device in said chamber adapted to lock said plate against movement, a door for closing said chamber, and means adapted to connect said door when closed to said slideable plate and thereby render the door locked when said slideable plate is locked. 75

3. The combination of a latch chamber, a slideable plate in said chamber, a hinged member adapted to swing down and lock said slideable plate, a door for closing said chamber, means adapted to connect said door when closed to said slideable plate and thereby render the door locked when said slideable plate is locked, and a key for raising said hinged member and thereby unlock said slideable plate. 80

4. The combination of a latch chamber, a slideable plate in said chamber, a hinged member adapted to swing down and lock said slideable plate, a door for closing said chamber, means adapted to connect said door when closed to said slideable plate and thereby render the door locked when said slideable plate is locked, a locking device adapted to lock said hinged member down, and a key for raising said hinged member and thereby unlock said slideable plate. 90

5. The combination of a latch chamber, a door for closing said chamber, a hinged member in said chamber, means adapted whereby said door is locked when closed and when said hinged member is down, a locking device adapted to lock said hinged member down, a key through which said locking device may be manipulated, and a key for raising said hinged member and thereby unlock said door. 105

6. The combination of a latch chamber, a main door, a latch carried by said main door and adapted to enter said chamber, means for securing said latch in said chamber and thereby prevent the opening of said main door, a permutation locking device in said chamber adapted to lock said door which closes the chamber, and a key through which said locking device may be manipulated. 110

7. The combination of a latch chamber, a door for closing said chamber, a hinged member in said chamber adapted to swing down and lock said door, a permutation locking device adapted to lock said hinged member down, a key through which said locking device may be manipulated, and a key for raising said hinged member and thereby unlock said door. 120

8. In a locking device comprising a base element, cross beams having slots carried by said base, a slideable plate carried by said base 130

under said cross beams and also provided with slots, a frame structure, lock strips forming part of said frame structure and adapted to engage the slots in said slidable plate, said strips having slots adapted to register with the slots in said cross beams when engaged with said slidable plate, a plurality of double end levers pivoted to said base element, and a locking block pivoted to one end of each of said levers, said locking blocks being reversible on said locking levers and adapted to engage either one of two pairs of said registered slots.

9. In a locking device comprising a base element, a plurality of locking levers pivoted to said base, a frame structure surrounding said levers, a crosshead slidable on said frame structure over the ends of said levers, and a slidable block carried by said crosshead adapted to slide in a transverse direction to the sliding movement of the

crosshead and further adapted to engage with the ends of said levers for moving the same.

10. In a locking device comprising a base element, a plurality of locking levers, a frame structure, a crosshead adapted to slide over the ends of said levers, a slidable block carried by said crosshead adapted to slide in a transverse direction to the sliding movement of the crosshead and further adapted to engage with the ends of said levers to move the same, a key adapted to slide in said crosshead and move said slidable block, a graduated scale aligned with the movement of said crosshead, and a pointer carried by said key and adapted to coact with said graduated scale to indicate the location of said slidable block.

In testimony whereof I affix my signature.

DENIS J. O'SULLIVAN.
